UNITED STATES PATENT OFFICE.

ROBERT W. SCOTT, OF LEEDS POINT, NEW JERSEY, ASSIGNOR TO SCOTT & WILLIAMS, INCORPORATED, A CORPORATION OF MASSACHUSETTS.

KNITTING-MACHINE.

1,251,586.

Specification of Letters Patent.

Patented Jan. 1, 1918.

Application filed March 17, 1911. Serial No. 615,163.

To all whom it may concern:

Be it known that I, ROBERT W. SCOTT, a citizen of the United States, residing in Leeds Point, Atlantic county, New Jersey, 5 have invented certain Improvements in Knitting-Machines, of which the following is a specification.

My invention relates to a knitting machine employing spring beard needles, the 10 object of my invention being to so construct such a machine that the feeding of the knitting yarn to the needles and the closing of the beards of the latter can be effected by mechanism of a much simpler character than 15 that usually employed, the size of the stitches being dependent upon the draft of the needles as in an ordinary latch needle knitting machine.

In the accompanying drawing I have 20 illustrated the application of my invention to a machine of the type shown in the Mayo Patent No. 726,178, dated April 21, 1903.

Figure 1 being a vertical sectional view of sufficient of the machine to illustrate 25 those parts of the same to which my invention particularly relates, the needle being shown in the position to which it is elevated during the knitting operation;

Fig. 2 is a similar view showing the needle 30 partially retracted and the beard closed;

Fig. 3 is a plan view illustrating the means employed for operating the ring which carries the yarn feeder and beard closer;

Fig. 4 is a view on a different scale from Fig. 1 illustrating the relation of the knitting cams, yarn guide, and beard closer in 35 respect to one another when the machine is running in one direction, and

Fig. 5 is a similar view illustrating the 40 relation of the parts when the machine is running in the opposite direction.

In the drawing, 1 represents part of the 45 needle cylinder of the machine, grooved externally for the reception and guidance of the needles 2 which are of the spring beard type, the upper portion of the stem of each needle being bent or offset outwardly below the beard, so that said bearded portion of 50 the needle is in advance of the main stem, as shown in Figs. 1 and 2.

The needles are intended to be vertically reciprocated by any suitable mechanism, such for instance as the cams α , α' , Figs. 4

and 5, for reciprocating the needles of the 55 Mayo machine before referred to.

Externally mounted on the upper portion of the main cylinder is a ring 3, in which is radially guided a series of web holding jacks 4, the latter operating between the needles and radial reciprocation being imparted to the jacks at the proper time by means of a cam ring 5 rotatably mounted upon the ring 3 and having motion imparted to it by the means shown in 60 the Mayo patent or any other equivalent devices. In drawing the stitch, the new yarn first rests upon the highest horizontal face of the web holding jack 4, that is to say on the top of the hook of the same, until the 65 beard of the needle has been closed by the presser, as shown in Fig. 2. The web holder is then withdrawn, as in the machine of the Mayo Patent, 726,178, above referred to, and the loop is drawn down on to the next lower 70 horizontal face of the web holding jack.

The needle continues its downward movement, the termination of such movement bringing the hook of the needle so far below said last mentioned horizontal face of the 75 web holding jack as to determine the size of the stitch, in the same manner as a latch needle, the web holder being then projected, as in the machine of the Mayo patent, so as to knock the stitch over the needle hook 80 and subsequently act to prevent the rise of the stitch with the needle on the next projection of the latter. It will be noted that the hooks of the needles are relatively open 85 so that the knitting yarn may reeve freely through the same in order to properly supply yarn to the stitch which is being drawn by a preceding needle.

At the top of the machine is a ring 6 which carries the yarn guide 7, the latter 90 having, at its lower end, a projecting finger 7^a with yarn guiding eye, the latter serving to deliver the yarn in front of the needles 2 and just below the offset portions of the same when said needles are lifted to the yarn 100 receiving position shown in Fig. 1. The ring 6 is rotated or reciprocated with the cam cylinder 9 by reason of the contact of one or other of a pair of drivers 10 on said cylinder with a pin 11 projecting from one 105 of the supporting standards of the ring 6, as shown in Fig. 3, the drivers 10 being properly spaced so as to provide the neces-

sary lost motion for insuring the proper lead of the yarn guide over the needle actuating cams when the direction of motion of the machine is reversed, as shown in Figs. 5 4 and 5.

To the ring 6 is also secured a beard presser 12 having, by preference, a beveled inner face, this beard presser being so disposed in respect to the needles and needle actuating cams that as the needles are being drawn downwardly the beard will come into contact with said inner face of the beard presser and will be closed thereby and held closed until the point of the beard has passed through the previously formed stitch which is hanging on the shank of the needle, forward movement of the beard presser then taking it out of contact with the beard, so that the latter is not acted upon by the beard presser during the further retraction or subsequent rising movement of the needle. The knitting yarn which has been laid by the yarn feeder 7 in front of the needle stems is, as each needle is retracted, caused to cling closely to the face of the forward swell or bend in the needle stem, and hence passes freely into the open beard as the needle descends, the beard being then closed so as to pass through the previous stitch and the loop of new yarn being drawn down through the latter as it is cast off from the top of the needle, as in the ordinary operation of spring beard needles.

The beard presser 12 moves with the yarn guide in shifting its position in respect to the knitting cams when the direction of motion of the machine is reversed, thus in Fig. 4 the beard presser bears such relation to the said knitting cams that it will properly act to close the beards of the needles when the latter are being retracted by the action of the right hand side of the retracting cam α , while in Fig. 5 the beard presser bears such relation to the knitting cams that it will act to close the beards of the needles when the latter are being retracted by the left hand side of said retracting cam α .

My invention provides for the ready conversion of an ordinary latch needle knitting machine into a spring beard needle machine by simply substituting for the latch needles the special type of spring beard needles shown and described and by providing the ordinary carrier ring for the yarn feeder 55 with a yarn feeding device and beard presser

such as shown in the drawing, all the other operating mechanism of the machine remaining the same as before.

While I have shown my invention as applied to a machine in which the needle cylinder is stationary and the cam cylinder rotates, it will be evident that the invention is equally applicable to that type of machine in which these conditions are reversed, the needle cylinder being the rotating member and the cam cylinder being fixed, and also to straight machines as well as to circular machines.

I claim:

1. The combination, in a knitting machine, of spring beard needles having their beard-carrying portions offset in advance of the main stems, with a yarn guide bearing such relation to said offset portions of the needles that the knitting yarn is laid below said offset beards when the needles have been projected to the yarn-receiving point.

2. The combination, in a knitting machine, of spring beard needles having their beard-carrying portions offset in advance of the stems of the needles, a guide for feeding the knitting yarn to the needles at a point below said offset beards when the needles are raised to receive the yarn, and a beard presser which, as the needles are retracted, acts upon the beards to close the same.

3. The combination, in a reversible knitting machine, of spring beard needles, cams for reciprocating the same, a yarn guide carrier movable in respect to the cams so as to properly feed the yarn to the needles whether the machine is running to the right or to the left, and a beard presser mounted upon said yarn guide carrier and moving with it.

4. The combination, in a knitting machine, of spring beard needles having a forward bend or offset immediately below the point of the beard with a yarn carrier bearing such relation to said offset portions of the needles as to lay the yarn in front of the needles below said offset.

In testimony whereof, I have signed my name to this specification, in the presence of two subscribing witnesses.

ROBERT W. SCOTT.
